CORSET

Joseph J. Kispert, Hamden, Conn.

Application October 14, 1938, Serial No. 234,879

13 Claims.

(Cl. 2-27)

This invention relates to corsets and more particularly to corsets of the type having a vest for holding the corset in place prior to lacing the body thereof.

5 In corsets of this type the vest may be made of elastic material or may consist of a front panel attached to the body by an elastic web or webs. It has been found, however, that the elastic, coming in contact with the flesh, causes perspiration and that body acids tend to attack the elastic and injure the same. In order to reduce the perspiration and also to make the garment lighter, the vest panel may be attached to the body by spaced elastic strips. In that event, 10 however, the flesh tends to bulge through the spaces between the strips. This not only produces discomfort, but prevents the proper positioning and action of the corset.

An object of the present invention is to provide 20 a novel and improved garment of the above type in which the above mentioned disadvantages are eliminated.

Another object is to provide a novel and improved garment of the above type which is light 25 in weight and in which the elastic portions are shielded from contact with the flesh so that the life of the elastic is greatly increased.

Another object is to provide, in such a garment, means for renewing the above mentioned 30 elastic when desired.

A further object is to provide a garment of the above type having an inner flap attached to the body which is adapted to cover the elastic portion of the vest and to shield the same from contact with the flesh.

35 A still further object is to provide means to prevent the inner flap from rolling or wrinkling when the body portion is pulled together in lacing.

40 A still further object is to provide means for causing the inner flaps to slide over the vest with the outer flaps when the latter are pulled together in lacing.

A still further object is to provide a garment 45 of the above type which is neat and pleasing in appearance and may be worn with a maximum degree of comfort.

Various other objects and advantages will be apparent as the nature of the invention is more 50 fully disclosed.

Although the novel features which are believed to be characteristic of this invention are pointed out more particularly in the claims appended hereto, the invention may be better understood by referring to the following descrip-

tion, taken in connection with the accompanying drawings, in which certain embodiments thereof have been set forth for purposes of illustration.

In the drawings,

Fig. 1 is a front elevation of a corset embodying the present invention, illustrating the same as applied to a person, with the vest fastened to hold the elastic under tension and with one of the front flaps pulled open to show the construction thereof, the stitch securing the inner and outer flap together being shown as broken to release the front flap.

Fig. 2 is a similar view showing the front flaps closed and the garment fully laced;

Fig. 3 is a plan view of the garment with parts broken away to show the construction of the vest;

Fig. 4 is a section taken on the line 4-4 of Fig. 1;

Fig. 5 is a partial detail view showing a different embodiment of the invention in which the inner panel is held by an elastic attached to the vest; and

Fig. 6 is a similar detail view showing a further embodiment of the invention in which the vest is held by elastic lacing and in which the front panel is turned back to expose the same.

In the following description and in the claims, certain specific terms are used for convenience 30 in referring to various details of the invention. It is to be understood, however, that these terms are to be given as broad an interpretation as the state of the art will permit.

In the accompanying drawings the invention 35 is shown as applied to a front-lace corset. It is to be understood, however, that the invention may also be applied to a back-lace corset or a side-lace corset and that the lacings can be replaced by other suitable holding means, such as 40 buttons, hooks and eyes, snap fasteners or the like, the lacings being referred to for convenience in designating this type of garment and not by way of limitation.

Referring to Figs. 1 to 4, the invention is 45 shown as applied to a corset 1 which is of the usual and standard construction and may comprise a plurality of fabric panels 2 (Fig. 3) which are constructed and arranged to encircle the body of the wearer when the corset is in place. 50 The corset may be provided with top and bottom gussets 3 and 4 respectively of elastic material or certain of the panels may be made of elastic material, it being understood that this portion of the garment is a standard and usual 55

construction and forms no part of the present invention.

The body of the corset terminates at edges 6 and 7, outer front flaps 8 and 9 being attached to the body at the edges 6 and 7 respectively or being formed as a continuation of the body portion. These flaps 8 and 9 may be provided with the usual hooks 10 at their free edges which are adapted to receive lacings 11 in the usual manner. It is to be understood, however, that the hooks 10 may be replaced by eyelets or other fastening means if desired. The hooks 10 preferably extend over the upper portion of the free edge of the flaps 8 and 9, at which portion stays 12 are provided to hold the edges in shape. Below the bottom end of the stays 12 the garment may be provided with a plurality of eyelets 14 which are adapted to receive a lace 15 of stretchable material, such as rubber. It is to be understood, of course, that the eyelets 14 could be replaced, if desired, by other means such as hooks, for holding the stretchable lace.

The vest portion of the garment comprises fabric panels 20 and 21, which may be made of cloth or other similar material and are provided at their free edges 22 and 23 respectively with cooperating fastening means, such as posts 24 and straps 25. Other separable fastening means, such as hooks and eyes, buttons, snap fasteners, or the like may, however, be used. These free edges are preferably also provided with stays 26 which hold the vest in shape. The stays may terminate at a point above the bottom of the vest to provide the necessary flexibility of the garment to accommodate the different positions of the wearer. The vest panels 20 and 21 may be attached to the body of the garment at the edges 6 and 7 by a plurality of elastic strips 28 and 29 respectively, formed of suitable material, such as rubber or lastex, and preferably spaced apart so as to provide ventilation between the strips as well as reduce the weight of the garment. The strips 28 and 29 may be attached to the vest panels 20 and 21 and to the edges 6 and 7 of the body portion by suitable rows of stitches.

The body portion is also provided with a pair of inner flaps 30 and 31 which are attached to the edges 6 and 7 respectively or are formed as a continuation of the body portion. The flaps 30 and 31 are made sufficiently long to overlie the elastic strips 28 and 29 when the strips are extended to their position of maximum stretch. Suitable stiffening members, such as stays 32 and 33 may be positioned along at least the upper portion of the free edges of the panels 30 and 31 respectively so as to hold the same in shape.

The inner flaps 30 and 31 are preferably co-extensive with the front flaps 8 and 9 and are attached thereto at the bottom and top edges, as by suitable rows of stitches, so as to form pockets in which the vest portions are adapted to slide.

The vest panels 20 and 21, in the embodiment shown, are provided with openings 34 and 35 respectively which are elongated in the direction of stretch of the elastic strips 28 and 29. The inner flaps 30 and 31 are secured to the outer flaps 8 and 9 respectively by suitable means, such as stitches 36 and 37 which extend through the openings 34 and 35 respectively. These stitches are sufficiently tight to cause the inner and outer flaps to move as a unit, but are sufficiently loose to permit free movement of the vest panels with respect thereto. The stitch 36 is shown as broken in Fig. 1 to permit the front flap to be pulled open to expose the strips 28. It is to be understood

that in use this flap lies flat against the vest panel 20 with the stitch 36 holding the inner flap 30 and the outer flap 8 together.

The corset may also be provided with abdominal supports 40 and 41, as shown in detail in Fig. 3, which may be secured to the edges of the vest panels 20 and 21 and may extend backwardly over at least the first panels of the body portion.

In applying this corset, the body of the corset is wrapped around the wearer and the vest panels 20 and 21 are brought together and fastened by means of the posts 24 and the straps 25. Sufficient force must be used to stretch the elastic strips 28 and 29 so as to cause the garment to conform generally to the shape of the wearer and to be held firmly in place. In adjusting the panels, the thumbs may, if desired, be extended through the openings 34 and 35 so as to assist in applying the necessary tension to the elastic strips. It is to be understood that the thumb openings may be used in other types of corsets for the same purpose. They may be particularly useful in back-lace corsets or in any lace corset to permit the same to be grasped for pulling the parts together. These openings are preferably located near the lower ends of the stays but may be placed at any other intermediate position.

After the vest panels have been joined, the garment is in the position shown in Fig. 1. The front panels may then be adjusted by applying the lace 11 to the hooks 10 and exerting sufficient force to shape the garment as desired. The lower parts of the front panels are preferably secured by an elastic lace 15 which is passed through the eyelets 14.

It will be noted that as the front panels are pulled together by the lacings, they slide over the vest panels 20 and 21. The inner flaps 30 and 31, being secured to the front flaps 8 and 9 at the top and bottom and also at an intermediate point by means of the stitches 36 and 37, are caused to slide with the outer flaps. The inner flaps are accordingly prevented from buckling up or wrinkling and are caused to lie smooth against the flesh of the wearer. Furthermore, these flaps fully conceal the elastic strips 28 and 29 and prevent the same from coming in contact with the flesh. The inner flaps serve not only to protect the elastic strips against perspiration and thereby increase the life thereof, but also prevent the flesh from bulging in the openings between the strips. The elastic strips may accordingly be spaced as widely apart as desired without interfering with the effectiveness of the corset in controlling the flesh.

It is to be noted that the openings 34 and 35 provide stops for the stitches 36 and 37 and thereby limit the movement of the vest panels with respect to the inner and outer flaps. This limits the amount of stretch of the strips 34 and 35 and also ensures that the inner and outer flaps will at all times cover and conceal the strips. It is to be understood, of course, that a plurality of such openings and stitches may be placed along the free edges of the inner and outer flaps, a single stitch located at the center of such edges having been shown merely for the purposes of illustration. It is also to be understood that in place of the stitches 36 and 37 other securing means may be employed, such as a button, snap fastener or the like. The vest panel may, if desired, be made in a plurality of spaced sections between which the stitches or other fastening means may be positioned. The inner flaps may of course

terminate at a point to conceal the elastic strips 28 and 29 when the garment is laced up but not to underlie the vest panels. In that event the inner and outer flaps may be secured together, 5 as by stitches, between the strips 28 and 29 to form pockets in which said strips slide.

In the embodiment shown in Fig. 5 the various parts of the garment are similar to that shown in Fig. 1, with the exception of the openings 34 and 36 in the vest panels and the corresponding 10 stitches 36 and 37. In this embodiment the openings and stitches are omitted and the inner flap 30 is attached to the edge of the vest panel 20 by means of an elastic strap 42. This strap 15 42 exerts sufficient tension, after the vest has been adjusted as in Fig. 1, to cause the free edge of the inner flap 30 to follow the movement of the outer flap 8 as the garment is adjusted by lacing. The operation is the same as that shown 20 in Fig. 1 except that the inner flap is held in a flat condition by means of the elastic strap 42 instead of by the stitch 36. It is to be understood, of course, that a plurality of straps 42 may 25 be used, if desired, which may be spaced along the corresponding edges of the inner flap and of the vest panel.

In the embodiment shown in Fig. 6, the inner and outer flaps are constructed in the manner shown in Fig. 1 except that the straps are not 30 stitched at the top and bottom and are provided with snap fasteners 45 by which they may be held together. In this way the outer flap 8 may be unsnapped and folded back when desired. In this embodiment the elastic strips 28 and 29 are 35 omitted and the vest panel 20 is attached to a fabric strip 48 by means of elastic laces 49. The strip 48 is stitched or otherwise secured to the edge 6 of the body of the garment. In this embodiment a separable fastener 50 is provided in 40 place of the stitch 36 of Fig. 1 so as to permit the outer flap to be detached for folding back. The garment is applied in the same manner as the garment of Fig. 1. The elastic lacing, however, is replaceable and may be renewed when damaged 45 or worn. Furthermore, the tension thereof may be adjusted to suit the wearer. It is to be understood, of course, that the flaps in this embodiment may be stitched, if desired, or that buttons or other fasteners may be used in place of the 50 snap fasteners shown.

In the garments above described, the vest portion may be made comparatively narrow, if desired, instead of extending substantially the full 55 length of the body as shown or it may be made in two or more vertically spaced sections, the arrangement being generally intended to provide sufficient tension for holding the garment in place during the lacing operation. After the garment has been laced, the tension on the vest section is relieved and the elastic strips are not relied upon for holding the garment to the desired contour.

It is to be understood that the abdominal support may be omitted, if desired, or in certain instances may be extended so as to cover a greater portion of the body. If desired, an elastic strap may be placed at the bottom of the garment to hold the hips. In any event, the vest facilitates the positioning and holding of the garment while 70 the same is being laced up.

Although certain specific embodiments of the invention have been shown for purposes of illustration, it is to be understood that various changes and modifications may be made therein 75 as will be readily apparent to a person skilled in

the art. The invention is only to be limited in accordance with the following claims when interpreted in view of the prior art.

I claim:

1. In a corset of the type described, a body having an opening, a two-part vest adapted to span said opening, elastic means securing said vest to said body, separable fastening means for securing the two parts of said vest and holding said elastic means under tension, outer flaps secured to said body to overlie said vest, said flaps being adapted to be pulled together over said vest for securing the corset in position, inner flaps secured to said body to underlie said elastic means when the corset is in wearing position so as to prevent the elastic means from contacting the flesh of the wearer, and connecting means causing the inner flaps to slide with said outer flaps over said vest as the outer flaps are pulled together so that the inner flaps are held flat and are prevented from wrinkling due to adjustment of the corset. 20

2. A corset according to claim 1 in which the connecting means connects the free edges of said inner flaps to said outer flaps. 25

3. A corset according to claim 1 in which the connecting means connects the inner and outer flaps together at spaced points.

4. A corset according to claim 1 in which the connecting means joins the inner and outer flaps along their bottom and top edges to form pockets 30 in which the vest slides.

5. A corset according to claim 1 in which the vest is provided with openings extending circumferentially intermediate its top and bottom 35 edges and the connecting means extends through said openings to secure the inner and outer flaps together.

6. A corset according to claim 1 in which the vest is provided with openings extending circumferentially intermediate its top and bottom edges and the connecting means comprises stitches extending through said openings to secure the inner and outer flaps together. 40

7. A corset according to claim 1 in which the vest is provided with openings extending circumferentially intermediate its top and bottom edges and the connecting means comprises separable securing means extending through said 45 openings to secure the inner and outer flaps together. 50

8. A corset according to claim 1 in which the vest is provided with openings extending circumferentially intermediate its top and bottom edges and the connecting means comprises securing means extending through said openings to 55 secure the inner and outer flaps together, said openings providing stops to limit the sliding movement of said vest with respect to said flaps.

9. A corset according to claim 1 in which the vest is provided with openings extending circumferentially intermediate its top and bottom edges and the connecting means comprises separable securing means at the top and bottom edges of the inner and outer flaps and at said openings. 65

10. A corset according to claim 1 in which the connecting means comprises elastic means joining the free edges of the inner flaps to the free edges of the vest.

11. A corset according to claim 1 in which the elastic means comprises a replaceable elastic lacing and the connecting means comprises separable securing means connecting the outer flap to the inner flap so that the outer flap may be folded back to expose the lacing. 70

12. A corset according to claim 1 in which stays are provided along the free edges of the inner and outer flaps and the connecting means joins said flaps at the top and bottom edges to form pockets in which the vest slides.

5 13. A corset according to claim 1 in which

stays are provided along the free edges of the inner and outer flaps and the connecting means joins said flaps at the top and bottom edges and at an intermediate point to form pockets in which the vest slides.

JOSEPH J. KISPERT.
